UNITED STATES PATENT OFFICE.

JOHN M. SAILER, OF PORTLAND, MICHIGAN.

PUNCHING AND SHEARING MACHINE.

SPECIFICATION forming part of Letters Patent No. 271,477, dated January 30, 1883.

Application filed April 4, 1882. (No model.)

To all whom it may concern:

Be it known that I, JOHN M. SAILER, of Portland, in the county of Ionia and State of Michigan, have invented a new and Improved 5 Punching and Shearing Machine, of which the following is a full, clear, and exact description.

The object of my invention is to provide a new and improved punching and shearing machine which is of simple construction and is 10 very powerful and durable.

The invention consists in a punching and shearing machine constructed with one jaw pivoted in the machine-frame and the other jaw connected with this pivoted jaw by means 15 of link-bars pivoted to the sides of both jaws. The jaws are provided on the adjoining edges with guide-lugs resting sidewise against each other, for preventing lateral movement of the jaws. The jaws can be operated by means of 20 a right-and-left-hand screw by a cam or other suitable device.

Reference is to be had to the accompanying drawings, forming a part of this specification, in which similar letters of reference indicate 25 corresponding parts in all the figures.

Figure 1 is a longitudinal elevation of my improved punching and shearing machine, parts being shown in section. Fig. 2 is a cross-sectional elevation of the same on the line *xx*, 30 Fig. 1. Fig. 3 is a detail cross-sectional elevation of the guides and shears on the line *yy*, Fig. 1.

An upper jaw, A, and a lower jaw, B, are coupled by two link-bars, C, one on each side 35 of the jaws, which link-bars are made very strong and heavy, and are pivoted to the jaws. Each jaw is provided in its rear end with a loosely mounted or pivoted nut, A'B', through which a vertical right-and-left-hand-threaded 40 screw, D, passes, the lower end of this screw resting on the base E of the machine. That part of the screw passing through the upper jaw, A, is threaded in one direction and that part passing through the lower jaw, B, is threaded in the opposite direction. The lower jaw, B, is pivoted by means of a pintle, F, between 45 two standards, G, on the base E. The punch-holder H is pivoted in the front part of the upper jaw, A, by a pintle, I, and has its upper and lower ends guided in two apertured trans-

verse plates J, held to the standards G. The die-holder K is pivoted in the front part of the lower jaw, B, by means of the pintle F, as shown. Two lugs, L L, project from the upper edge of the lower jaw, B, and two like or similar lugs, M, project from the lower edge of the upper jaw, A, the adjoining or inner surfaces of these lugs resting against each other, which lugs serve to guide the jaws in their movements and prevent lateral movement of the jaws on 55 each other. The shear-blades N are attached to projections or lugs O, projecting from the edges of the jaws between the lugs L L and M M. In place of the right-and-left screw, a cam or any other suitable device may be used 60 to operate the jaws.

The operation is as follows: If the rear ends of the jaws are separated, the lower jaw will be lowered and the link-bars C will draw the front end of the upper jaw downward slightly, 70 the lower jaw turning on the pintle F and the upper jaw turning on the upper pivots of the link-bars C. At the same time, the rear end of the upper jaw being raised, the front of this upper jaw is pressed downward, and the punch 75 is forced through the material into the die, the pivoted die-holder H moving longitudinally in its guides J. To cut with the shears, the rear ends of the jaws must be brought together, the lower jaw swinging on its pintle F and the 80 upper jaw swinging on the upper pivots of the link-bars C. The lower jaw is raised and the upper jaw is raised by the link-bars C; but its rear part is lowered more rapidly by the screw or other device, so that this upper jaw 85 will be raised at its front part and will be lowered or depressed at its rear part, so that the crossing-point of the sharp blades will move toward the front part of the machine on a curved line. In both operations most of the 90 strain will be taken from the frame and will be mainly on the link-bars C and their pivots, which must be made very strong.

Having thus described my invention, I claim as new and desire to secure by Letters Patent— 95

1. A punching and shearing machine constructed substantially as herein shown and described, with two jaws connected by pivoted link-bars, as set forth.

2. In a punching and shearing machine, the 100

combination, with a jaw pivoted in the machine-frame, of a jaw connected with this pivoted jaw by link-bars pivoted to both jaws, substantially as herein shown and described, and for the purpose set forth.

3. In a punching and shearing machine, the combination, with a jaw pivoted in the machine-frame, of a jaw connected with this pivoted jaw by link-bars pivoted to each jaw, and of 10 guide-lugs projecting from the adjoining edges of these jaws, the inner surfaces of these lugs resting against each other, substantially as herein shown and described, and for the purpose set forth.

15 4. In a punching and shearing machine, the combination, with a jaw pivoted in the frame of the machine, of a jaw connected with this pivoted jaw by link-bars pivoted to each jaw,

and of a right-and-left-hand screw passing through these jaws for operating them, substantially as herein shown and described, and for the purpose set forth.

5. In a punching and shearing machine, the combination, with the jaw B, pivoted on the machine-frame, the jaw A, connected with the jaw B by link-bars C, pivoted to both jaws of the punch-holder H, pivoted in the upper jaw, A, and the guide-plates J for this punch-holder, which guide-plates are attached to the machine-frame, substantially as herein shown and 30 described, and for the purpose set forth.

JOHN M. SAILER.
